[54] FEMALE BUSINESS CASE

[75] Inventor: Lelia M. Allen, Pittsburgh, Pa.

[73] Assignee: The Raymond Lee Organization, Inc., New York, N.Y.; a part interest

[22] Filed: Aug. 31, 1973

[21] Appl. No.: 393,400

[52] U.S. Cl. 150/1.6, 150/30, 150/33, 150/34

[51] Int. Cl. A45c 3/02

[58] Field of Search 150/30, 1.6, 28 R, 33, 150/34; 190/51

[56] References Cited

UNITED STATES PATENTS

1,719,040 7/1929 Barol 150/34
1,725,093 8/1929 Maksik ..... 150/33 UX

2,020,906	11/1935	Rolfs.....	150/34
2,096,768	10/1937	Styll.....	150/1.6
2,432,001	12/1947	Fisler.....	150/33 UX
2,712,337	7/1955	Tremblay.....	150/30 X
2,827,093	3/1958	Shenfield.....	150/30
3,020,945	2/1962	Brunner.....	150/3
3,347,299	10/1967	Alexander.....	150/34
D142,706	10/1945	Deutz.....	150/33 UX

Primary Examiner—Donald F. Norton

[57] ABSTRACT

A female business case comprising: a flexible hollow vertical purse-like member open at the top with a top flap for removably closing the top opening. The member has vertical sides with vertical folds permitting the member to be compressed or expanded between front and rear vertical surfaces. Means in the member removably holds at least one switch out folder.

1 Claim, 1 Drawing Figure

FEMALE BUSINESS CASESUMMARY OF THE INVENTION

My invention is directed toward a feminine business case designed for use by the female executive, business woman or student who finds the attache case cumbersome and unattractive when carrying an additional purse.

The case employs a flexible hollow vertical purselike member open at the top with a top flap for removably closing the top opening. The member has vertical sides with vertical folds permitting the member to be compressed or expanded between front and rear vertical surfaces. Means in the member removably holds at least one switch out folder.

The case can be made in various basic colors so as to match the owner's attire. Switch outs can be suitably colored.

BRIEF DESCRIPTION OF THE DRAWING

The accompanying drawing is a perspective view of a preferred embodiment of my invention.

DETAILED DESCRIPTION OF PREFERRED EMBODIMENT

Referring now to the accompanying FIGURE a hollow vertical flexible purse-like member 10 has a top opening, opposite vertical sides 12 having vertical folds 14 which permit the member to be compressed or expanded between front and rear vertical surfaces and a flap 16 which is a continuation of the rear surface and which can close the top opening with latch 18 (which can be designed or decorated and can be operated by a key lock) engaging flap opening 20.

Pouches for tablets 22 and for pens 24 can be secured to the inside of the flap. Vertical partitions 26 divide the member interior into separate regions which can store various items as well as storing removable switch out folders 28 which themselves can be zippered narrow cases.

An adjustable carrying strap can be secured to the purse member being widest at the base as shown at 30 and decreasing in width as the strap extends upward.

The invention can then be used as previously described.

While I have described my invention with particular reference to the drawings, such is not to be considered as limiting its actual scope.

Having thus described this invention, what is asserted as new and claimed is:

1. A female business case comprising:
 a flexible hollow vertical purse like member open at the top with a top flap for removably closing the top opening, said member having vertical outer sides with vertical folds permitting the member to be compressed or expanded between front and rear vertical surfaces;
 means secured to the inside surface of said top flap for removably storing tablets and pens;
 vertical partitions disposed in the interior of said member to divide the interior of said member into a plurality of vertical compartments;
 at least one switch out folder removably disposed in a corresponding compartment, said folder being a flexible, hollow, narrow container adapted to hold papers and the like and having a zippered opening; and an adjustable carrying strap secured to the outside of the member, said strap being wide at the base of the chamber and decreasing in width as the strap extends toward the top of the purse member.

* * * * *

40

45

50

55

60

65